CLAIM

I claim the ornamental design for a cutting mat, as shown.

DESCRIPTION

FIG. 1 is a perspective view of a cutting mat showing my new design;

FIG. 2 is a top plan view of the cutting mat as shown in FIG. 1;

FIG. 3 is a bottom plan view of the cutting mat as shown in FIG. 1;

FIG. 4 is a front elevational view of the cutting mat as shown in FIG. 1; and,

FIG. 5 is a side elevational view of the cutting mat as shown in FIG. 1.
